COMBINED FILING AND DISPLAY DEVICE

Martin Green, Mahwah, N. J.

Application April 15, 1949, Serial No. 87,721

4 Claims. (Cl. 40—102)

1

This invention relates to improvements in means for filing or storing a multiplicity of photographs, picture or other cards or sheets and like matter subject to selective display, and subject to easy selective removal and replacement if desired.

The invention has for an object to provide a novel filing or storing device for the stated purposes which is of very simple and inexpensive construction; which provides a large holding capacity for a multiplicity of items; each item being removably held in an individual transparent envelope or pocket-like receptacle; the device including a novel column or stand having means for detachably supporting the envelopes or receptacles for radial extension therefrom, and subject to such movement in connection with the supporting means, relative one to another, as to permit selective exposed disposition of an envelope or receptacle subject to display of its content.

Other objects of the invention, not at this time more particularly enumerated, will be understood from the following description of the same.

An illustrative embodiment of the invention is shown in the accompanying drawings, in which:

Fig. 1 is an elevational view of the filing and storing device; Fig. 2 is a top plan view of the same; Fig. 3 is a fragmentary longitudinal sectional view, taken on line 3—3 in Fig. 2, but drawn on a somewhat enlarged scale; Fig. 4 is another longitudinal sectional view, taken on line 4—4 in Fig. 2, also drawn on a somewhat enlarged scale; Fig. 5 is a horizontal sectional view, taken on line 5—5 in Fig. 3; Fig. 6 is another horizontal sectional view, taken on line 6—6 in Fig. 3; Fig. 7 is a top plan view showing part of the envelope or receptacle supporting means of the column or stand in opened condition; Fig. 8 is a plan view of an envelope or receptacle supporting means detached from the column or stand; and Fig. 9 is a side edge elevation of said supporting means.

Similar characters of reference are employed in the above described views, to indicate corresponding parts.

The novel filing or storing device according to this invention comprises a perpendicular column formed by a lower section 10 and an upper section 11. The lower column 10 is footed upon a hollow circular base shell 12 having a dependent peripheral skirt or side flange 13. Said lower section 10 is secured in assembled and supported relation to the base shell 12 by an anchor screw 14 having a head 15. The upper end of the lower column section 10 is provided with a screw-

2

threaded coupling shank 16 of reduced diameter, thus providing a shoulder 17 at the juncture of said shank with said lower column section. Said threaded shank 16 is adapted to screw into the lower end of the upper column section 11. Assembled with and between the thus jointed ends of the lower and upper column sections 10 and 11 is a circular top shell 18 which is also provided with a dependent peripheral skirt or side flange 19.

Assembled respectively in connection with the base shell 12 and with the top shell 18 are supporting elements upon which a plurality of envelopes or receptacles (hereinafter described) 15 can be detachably mounted. Each said supporting element consists in a formation produced from resilient or springy wire, and each such formation comprises a length of wire which is doubled upon itself to provide an eye loop 20 adapted to be disposed in vertical plane. One arm 21 of the eye loop 20 is adapted to be outwardly bowed in one direction in horizontal plane, and the other arm 22 of said eye loop is adapted to be outwardly bowed in the opposite direction in horizontal plane; the disposition of the rearward end portions of said arms be such that they preferably cross one another. The combined length of the eye loop 20 and its arms 21 and 22 substantially exceeds the diametric dimension of the base shell 12 and that of the top shell 18. One arm of the formation, e. g. the arm 21, is bent to form a semi-circular carrier member 23 which extends in one direction, and which terminates in a latching hook 24 adapted to be entered through the eye loop 20 so as to be releasably hooked thereto, whereby to close the carrier member 23. In like manner, the other arm of the formation, i. e., the arm 22, is bent to form a second semi-circular carrier member 25 which extends in the opposite direction, and which also terminates in a latching hook 26 adapted to be entered through the eye loop 20 so as to be releasably hooked thereto, whereby to close said second carrier member 25.

The said supporting elements are respectively assembled one with the base shell 12 and the other with the top shell 18, before said shells and the column sections 10 and 11 are joined in stand forming relation. To permit such assembly, each shell is provided in its skirt or side flange with diametrically opposite openings 27 and 28; the latter opening being preferably in the form of a perpendicular slot for reception of the eye loop 20, so as to assure retention of said eye loop in its normal vertical plane.

In assembling a supporting element with a

shell, the latching hooks 24 and 26 are disconnected from the eye loop 20, whereupon the eye loop end of the element is inserted through the opening 27 at one side of the shell to pass beneath the body of said shell, and thence through the opening 28 at the opposite side of said shell, so as to project exteriorly therefrom, and so that the rearward end portions of the arms 21 and 22 of the element are disposed to project exteriorly from said shell, whereby the respective carrier members 23 and 25 are disposed to concentrically encircle the exterior of the shell in outwardly offset spaced relation to the periphery thereof.

After a supporting element is assembled with the base shell 12, the latter is ready to be joined to the bottom end of the lower column section 10. This is done by passing the anchor screw 14 upwardly between the bowed arms 21 and 22 of the element, and thence through the body of the shell to screw into the bottom end of the column section 10, until the head 15 of the anchor screw binds against said arms 21 and 22, thus not only firmly fastening the column section 10 to the base shell 12, but, at the same time, securely binding the supporting element to the shell against shifting displacement from its proper assembled relation thereto. If desired, a washer 29 may be interposed between the head 15 of the anchor screw 14 and the arms 21 and 22 of the supporting element.

The top shell 18, with a supporting element assembled therewith, is next joined with the upper column section 11 to the upper end of the lower column section 10. This is accomplished by passing the screw-threaded coupling shank of the lower column section 10 between the bowed arms 21 and 22 of the supporting element assembled with the top shell 18, and thence through the latter to screw into the lower end of the column section 11, and so that the shoulder 17 of said lower column section 10 binds against said element arms 21 and 22, whereby not only is the top shell 18 and upper column section 11 firmly coupled together and to the lower column section 10, but also the supporting element is securely bound to the top shell 18 against shifting displacement from its proper assembled relation thereto. If desired a washer 30 may be interposed between the shoulder 17 and the arms 21 and 22 of the supporting element.

Upon assembly of the shells 12 and 18 and their supporting elements in connection with the joined column sections 10 and 11 in the manner above described, a stand structure is provided wherein the carrier members 23 and 25 of the supporting elements are vertically spaced apart ready to receive application thereto of the hereinafter described envelopes or receptacles of the device.

Corresponding carrier members 23 and 25 of the supporting elements, as assembled in connection with and as parts of the stand structure, are vertically spaced apart in aligned relation, and are thus adapted to support a multiplicity of envelopes or receptacles 32. Each envelope or receptacle 32 is made wholly, or at least in part, from transparent material, such e. g. as a transparent cellulosic sheet material, and is formed to provide an upwardly open pocket into which an item 33, such as a photograph, picture, or the like, may be inserted for filing or storage therein, so as to be visible through a transparent wall of

the envelope or receptacle. Each envelope or receptacle is provided in a longitudinal side marginal portion thereof with perforations which are vertically spaced in correspondence to the vertical spacing of the carrier members 23 and 25, whereby said envelope or receptacle may be threaded onto either the aligned carrier members 23 or the aligned carrier members 25, as the case may be, so as to extend therefrom in radial relation to the stand structure.

Preparatory to so mounting the envelopes or receptacles 32 on selected carrier members 23 or 25, the latching hooks 24 and 26 are disengaged from the eye loops 20 of the supporting elements, thus freeing the extremities of the carrier members for insertion through the perforate marginal portions of the envelopes or receptacles. After the carrier members 23 and 25 have been loaded with the envelopes or receptacles desired to be supported thereby, the latching hooks 24 and 26 are reengaged with the eye loops 20, thus closing the carrier members against escape therefrom of the envelopes or receptacles mounted thereon.

It will be obvious that a very considerable number of the envelopes or receptacles may be thus mounted on and supported by the carrier members 23 and 25, and that, when so mounted, said envelopes or receptacles can be moved on and swung relative to the carrier members, in manner similar to turning of the pages of a book, whereby to select and separate from its fellows any given envelope or receptacle so that the item 33 contained therein may be conveniently disposed for display or inspection.

From the above it will be apparent that the instant invention provides a very compact means for filing and storing a multiplicity of items subject to selective display, and also subject to easy selective removal and replacement when so desired.

Having now described my invention, I claim:

1. A device for the purposes described comprising a perpendicular column, a hollow base shell on which said column is footed, a hollow top shell affixed to said column in upwardly spaced relation to the base shell, each shell having a supporting element formed from wire to provide an eye loop disposed to radially project exteriorly from a side of the shell, said eye loop having a pair of arms extending diametrically across the shell in straddling relation to said column to project from the opposite side of the shell, said arms terminating in semi-circular carrier members extending respectively therefrom in opposite directions so as to be outwardly spaced in concentrically encircling relation to the shell exterior, each carrier member terminating in a latching hook releasably engageable with the eye loop, and upwardly open transparent envelopes adapted to be mounted on and between carrier members of said shells, whereby to extend radially outward therefrom.

2. A device for the purposes described comprising a perpendicular column, a base shell having dependent annular side walls, means for securing the column to the base shell for upstanding axial extension therefrom, a top shell also having dependent annular side walls, means for affixing said top shell to the column in upwardly spaced aligned relation to the base shell, each shell having diametrically aligned openings in its side walls, each shell having a supporting element formed from wire to provide an eye loop disposed to project exteriorly from the shell through one

side wall opening thereof, said eye loop having arms extending diametrically across the shell to project exteriorly therefrom through the opposite side wall opening thereof, said arms terminating in semi-circular carrier members extending respectively therefrom in opposite directions so as to be outwardly spaced in concentrically encircling relation to the shell exterior, each carrier member terminating in a latching hook releasably engageable with the eye loop, and upwardly open transparent envelopes having side marginal portions threaded over corresponding carrier members so as to extend therebetween and radially outward therefrom.

3. A device for the purposes described comprising a hollow base shell, a hollow top shell, a lower column section, fastening screw means engaged through the base shell whereby to secure said lower column section thereto, an upper column section, fastening screw means connected with the upper end of the lower column section engaged through the top shell whereby to secure said top shell and upper column section to the lower column section, a supporting element mounted in connection with each shell including a single eye loop disposed to radially project exteriorly from the side of the shell and carrier members having end portions disposed to radially project exteriorly from the diametrically opposite side of the shell, said carrier members being of semi-circular shape to extend in opposite directions in concentrically encircling and outwardly spaced relation to the shell, each carrier member terminating in a latching hook releasably engageable with the eye loop, and upwardly open transparent envelopes having side marginal portions thereof threaded over corresponding carrier members so as to extend therebetween and radially outward therefrom.

4. A device for the purposes described comprising a base shell having dependent annular side walls, a top shell also having dependent an-

nular side walls, each shell having diametrically aligned openings in its side walls, each shell having a supporting element formed from wire to provide an eye loop disposed to project exteriorly from the shell through one side wall opening thereof, said eye loop having outwardly bowed arms extending diametrically across the shell interior to project exteriorly therefrom through the opposite side wall opening thereof, 5 said arms terminating in semi-circular carrier members extending respectively therefrom in opposite directions so as to be outwardly spaced in concentrically encircling relation to the shell exterior, each carrier member terminating in a latching hook releasably engageable with the eye loop, a lower column section fastening screw means engaged through the base shell and extending between the eye loop arms of its supporting element, whereby to secure said lower column section to the base shell, an upper column section, fastening screw means connected with the upper end of the lower column section engaged through the top shell and extending between the eye loop arms of its supporting element, whereby to secure the upper column section and said top shell to the lower column section, and upwardly open transparent envelopes having side marginal portions thereof threaded over corresponding carrier members so as to extend therebetween and radially outward therefrom.
